(57) **CLAIM**

The ornamental design for shoe, as shown and described.

DESCRIPTION

FIG. 1 is a side view of a shoe showing our new design; FIG. 2 is a rear perspective view thereof; FIG. 3 is a rear view thereof; FIG. 4 is an opposite side rear perspective view thereof; and, FIG. 5 is an opposite side view thereof.

The broken line immediately adjacent to the shaded area defines the bounds of the claimed design and forms no part thereof. The broken line showing of the two rectangular areas within the shaded region forms no part of the claimed design. The broken lines depicting the remainder of the shoe form no part of the claimed design.

1 Claim, 5 Drawing Sheets
